US00D757345S

(12) **United States Design Patent**
Martinez

(10) **Patent No.:** **US D757,345 S**
(45) **Date of Patent:** **** May 24, 2016**

(54) **LIGHT FIXTURE**

(71) Applicant: **Art Design Works LLC**, Lexington, MA (US)

(72) Inventor: **Carl Martinez**, Easton, PA (US)

(73) Assignee: **Art Design Works LLC**, Lexington, MA (US)

(**) Term: **14 Years**

(21) Appl. No.: **29/502,022**

(22) Filed: **Sep. 10, 2014**

(51) LOC (10) Cl. **26-99**

(52) **U.S. Cl.**
USPC **D26/118**

(58) **Field of Classification Search**

(57) **CLAIM**

The ornamental design for a light fixture, as shown and described.

DESCRIPTION

FIG. 1 is a top, front, left side perspective view of the light fixture showing a first embodiment thereof;
FIG. 2 is a left side elevation view of FIG. 1;
FIG. 3 is a right side elevation view of FIG. 1;
FIG. 4 is a rear elevation view of FIG. 1;
FIG. 5 is a front elevation view of FIG. 1;
FIG. 6 is a top plan view of FIG. 1;
FIG. 7 is a bottom plan view of FIG. 1;
FIG. 8 is a top, front, left side perspective view showing a second embodiment thereof;
FIG. 9 is a left side elevation view of FIG. 8;
FIG. 10 is a right side elevation view of FIG. 8;
FIG. 11 is a rear elevation view of FIG. 8;
FIG. 12 is a front elevation view of FIG. 8;
FIG. 13 is a top plan view of FIG. 8; and,
FIG. 14 is a bottom plan view of FIG. 8.

The broken lines represent portions of the light fixture that form no part of the claimed design. The stippled portions represent contrasting material portions of the claimed design. The dash-dot broken lines form no part of the claimed design and represent boundaries of the contrasting material portions of the claimed design.

1 Claim, 13 Drawing Sheets
